UNITED STATES PATENT OFFICE.

SAMUEL LAUTERBACH, OF NEW YORK, N. Y.

JEWELRY CLASP.

Application filed January 4, 1927. Serial No. 158,873.

This invention relates to articles of jewelry and has particular reference to attaching devices for such articles of jewelry and particularly for the attachment of bracelets, 5 brooches, or other devices having separable links.

Among the objects of the invention is to provide a fastener that is self-locking and so constructed that when strain is brought 10 to bear upon it, such strain will serve but one purpose, namely, to hold the device the more firmly locked or sealed.

With the foregoing and other objects in view the invention consists in the arrangement and combination of parts hereinafter described and claimed, and while the invention is not restricted to the exact details of construction disclosed or suggested herein, still for the purpose of illustrating a practical embodiment thereof reference is had 20 to the accompanying drawings in which like reference characters designate the same parts in the several views, and in which—

Figure 1 is a side elevation of the clasp 25 closed.

Fig. 2 is a similar view with the clasp partially open.

Fig. 3 is a view showing the clasp well 30 open as for the attachment of another member.

Fig. 4 is an enlarged view in vertical longitudinal section.

Fig. 5 is an end view of the device closed and as would be seen looking toward the left 35 in Fig. 4.

Fig. 6 is a diagram indicating one manner of use of the device.

Referring now more specifically to the drawings I show the clasp as comprising 40 two main parts 10 and 11 pivoted permanently together at 12 and one part as 11 having a hook 13 adapted to snap into a notch 14 formed in the other.

The member 10, adjacent to the pivot 12, 45 is bifurcated as shown best in Figs. 4 and 5 at 15, forming a slot 16 extending practically one-half the length of the member 10.

The other link member 11 is formed adjacent to the pivot 12 with a tongue 17 which 50 projects into the slot 16 filling the same when the clasp is closed. The tongue, however, radially of the clasp is materially wider than the other members, insuring that a portion thereof will lie within the open 55 space within the clasp. This member 11 with its tongue extension 17 is in the nature

of a lever of the first class or bell crank whose pivot or fulcrum is 12.

The hinge or pivot portion of the member 10 closely adjacent to the pivot and at the outside thereof has a combined stop and brace 18 formed integral with the end portions of the spaced members of the fork 15. Not only does this brace re-enforce this bifurcation, relieving the pivot 12 from any strain that may be brought upon the clasp, but it serves as a stop to limit the opening swing of the tongue member 11 as indicated in dot and dash lines in Fig. 4, a matter of considerable moment, considering that the clasp is ordinarily manipulated by one hand.

When the tongue member 11 is opened as it may be by exerting pressure of the thumb upon the projection 19 at or adjacent to the hooked end of the tongue member, it will assume the position, say of Fig. 3, permitting the next adjacent link 20 of the device to be slipped freely over the hooked end of the tongue member, the link 20 passing likewise freely over the pivot or joint portion of the two members 10 and 11 past the stop 18 and will find its seat in the crotch of the tongue member just beyond or within the pivot, as shown in Fig. 6, in which position the pull or strain of the link 20 upon the clasp will be borne directly upon the inner edge portion of the tongue 17, which projecting inward beyond the side portions of the fork 15 will insure that the strain 55 will be brought directly upon the bell crank or lever member. The hook 13 may or may not be used as desired, but when used it re-enforces the locking action and makes 60 secure the closed position.

Obviously the clasp may be made of any suitable metal or other material and of any desired size or configuration within the scope of the specific description set forth above.

I claim:

1. In a clasp, the combination of two members pivoted together and relatively movable around the axis of the pivot, the main portions of the members being of similar cross section, one of the members being forked and having a slot adjacent to the pivot, while the other has an extension beyond the pivot co-operating with the slot and forming a tongue integral and rigid 105 with the part that carries it, said tongue being wider radially of the clasp than the re- 110

mainder of the device, the extension of the tongue projecting into the interior of the clasp.

2. A device as set forth in claim 1 including means to limit the closing movement of the members whereby the strain brought upon the tongue is compelled to be borne thereby.

3. A device as set forth in claim 1 including a combined stop and brace member integral with the fork and located closely adjacent to the pivot and extending across the slot and serving to limit the opening swing of the tongue member.

In testimony whereof I affix my signature.

SAMUEL LAUTERBACH.
